(57) CLAIM

What is claimed is the ornamental design for a combined bottle and cap, as shown and described.

DESCRIPTION

FIG. 1 is a top, rear and left side perspective view of my new design for a combined bottle and cap;

FIG. 2 is a front elevation view thereof;

FIG. 3 is a rear elevation view thereof;

FIG. 4 is a left side elevation thereof;

FIG. 5 is a right side elevation thereof;

FIG. 6 is a top plan view thereof; and,

FIG. 7 is a bottom plan view thereof.

The broken lines shown in FIGS. 1-7 are for illustrative purposes only and forms no part of the claimed design.
